[57] CLAIM

The ornamental design for a contact lens case, as shown and described.

DESCRIPTION

FIG. 1 is a perspective view of a contact lens case showing our new design;

FIG. 2 is a side elevational view thereof;

FIG. 3 is a side elevational view of the side opposite the side shown in FIG. 2;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view of the integral cap and lens support structure of the contact lens case shown in FIGS. 1-7;

FIG. 9 is a top plan view thereof;

FIG. 10 is a front elevational view thereof;

FIG. 11 is a rear elevational view thereof;

FIG. 12 is a side elevational view thereof;

FIG. 13 is a side elevational view of the side opposite the side shown in FIG. 12; and,

FIG. 14 is a bottom plan view thereof.

The separate showing of the integral cap and lens support structure in FIGS. 8-14 is for ease of illustration only.
